CIRCUMORBITAL CUTTING TOOL

Donald U. Shaffer, Brea, Frank D. Hobbs, Huntington Beach, and Edward C. Hamm, Norwalk, Calif.

Application May 27, 1938, Serial No. 210,446

19 Claims. (Cl. 164—0.7)

This invention is a tool for cutting pipes, stems and other bodies which may lodge in a well hole and is an improvement in tools such as shown by Luther Patent 111,221, of June 1871, in which cutters are pivoted at their upper ends to hang in slots in one member and are engaged by a relatively slidable member to be forced inwardly to cut the opposed fish body in a well hole.

Luther shows no means for connecting the two members in a position preventing such relative movement as would swing the cutters inward, but such a provision is to be found in Anderson Patent 1,530,636, filed April 9, 1923, where the cutters are held as stops against member 19 which has means 21 to catch on the end of a drill pipe collar b. Thus as early as April 9, 1923, means had been provided to prevent relative movement of a member controlled by a pipe collar as to a relatively shiftable companion member as 14 of Anderson, without use of a conventional shear pin—old at the time.

The present invention has to do with a circum-orbital cutting tool involving a wholly different principle of operation than that of Luther's telescopic members and that of Anderson showing cutters used as restrainers, and that of Kammerer Patent 1,625,414, April 19, 1927, showing a tool which depends on a constant pull of the string to force cutters 11 in while the dogs 29 hold against the pipe collar, which is the mere reverse of Luther's cutting action.

Also the present invention is substantially different from Pickin Patent 1,772,085, August 5, 1930, showing a set of suspended cutters 15, as in Kammerer above mentioned, but which are positively locked in outer position by a sleeve 33 which is locked by a pin 39 on the rotary, unlocking tool body 11, positioned between the cutters and the axis of the tool as set out in each of his claims, and necessitating rotation of the tool body to unlock the cutters and then the lowering of the tool body as to the sleeve while this is intended to be frictionally held, by springs 37, on the pipe 47 before the cutters can be rammed inward by the sliding cam 19.

The above art is cited as showing different forms in which the pioneer Luther device has been embodied with increased complexity, and an object of the present invention is to provide a tool of this class which aims to eliminate several of the hazardous operations of the known art and to effect the actual cutting of the given fish body with the least possible manipulation of the tool string.

Particularly, an object is to provide a set of

tiltable cutters bodily shiftable as a set, and to provide for normally restraining the set, and for the release of the set of cutters by a very slight upward pull of the tool string after the tool assembly has been juxtaposed to engage the fish body against end shift in either, or at least one, direction whereby to have the function of merely releasing the set of cutters, and, further, an object is to provide an automatic means to shift the set of cutters and allow the cutters to completely perform the function of cutting the fish body entirely without other motion of the tool string than merely its rotation to swing the cutters orbitally with respect to the struck fish body, or object, if capable of being engaged in such a manner as to permit the cutting tool assembly to function.

A further object of the invention is to greatly simplify the organization, reduce the cost of construction, renewal, upkeep and operation both in power and labor requirements, to enable employment of lighter parts, and increase safety of operations in a tool of the type concerned.

An additional object is to provide a fish cutting tool, which by eliminating the common step of placing the string under tension to make the cut, enables the lowering of the set of cutters to any desired point between two incidental shoulders (like collars) on the engaged string section once the cutters have been released for cutting function.

Another object is to provide a cutting tool of the kind concerned, which may be operated to release its set of cutters, for shift as a unit, either by re-action of dogs against a shoulder on a fish body, or by means of mechanism which may be set at any desired elevation on a string with or without shoulders.

The invention consists in certain advancements in this art as set forth in the ensuing disclosure and having, with the above, additional objects and advantages as hereinafter developed, and whose construction, combinations and details of means, and the manner of operation will be made manifest in the description of the herewith illustrative apparatus; it being understood that modifications, variations and adaptations may be resorted to within the scope, principle and spirit of the invention as it is more directly claimed hereinafter.

Figure 1 is a sectional, side elevation of the tool, as provided with spring dogs designed to engage, by upward pull, against a shoulder part of or on a fish body which is to be severed at a point below the shoulder.

Figure 2 is a detail side elevation of the carrier (without the cutters) in relation to carrier releasing shears, before shear.

Figure 3 is a sectional elevation of pipe "slip" 5 embracing assembly employable in the tool to effect action of the tool shears for releasing the restrained set of cutters.

An annular set of cutters 2 is shown in which the lower ends of the individually tiltable cutters 10 are provided with pivots 3 suitably journaled in substantial cutter blocks 4 which are removably attached, in annular arrangement, about and on the upper end of a tubular carriage or herein called carrier 5. This carrier slidably fits in the 15 foot section 6 of a tool barrel including an upper section 7 joining the section 6 by screw threads 8.

The barrel section 6 has angularly spaced windows 9 to slidably receive the cutter blocks 4 which are readily mounted in the windows and 20 then fastened to the carrier by respective screws 10 in a simple and practical manner without having to knock down the barrel assembly, and the blocks 4 form splines to prevent rotation of the carrier in the barrel and they also transmit 25 torque to the carrier when the barrel is rotated as by means of a wash-over pipe 12 screwed onto the upper end of the barrel section 7; the pipe 12 being connected to a top, sub-joint 13 forming a part of a tool string by which the barrel assembly 30 is lowered and raised and rotated as desired, in a well hole for operation on and recovery of a stuck fish, such as pipe, tubing or drill stems, in the hole; a pipe body B being here illustrated with a collar C, over-shot by the tool in Fig. 1.

The foot end of the barrel is provided with a suitable shoe 14 to pass over the upper end of the fish body B and means are provided above the shoe to automatically force the tiltable cutters 2 into cutting engagement with the apposite fish 40 when the tool has been lowered into juxtaposition therewith, and this means as here shown includes a very strong spring 15 seating at its lower end on a stationary part, as the shoe 14, which here serves to compress the spring upwardly against 45 the lower end of the slidable carrier 5 with the function of bodily shifting the set of cutters upwardly in narrow portions 9a of the windows and in which are arranged rollers 16 for engaging the outer, cam faces 2a formed by the inward pitch 50 of the upper, cutting ends of the cutters 2.

To keep the cutters 2 in upright position, as shown, until they are to be forced into fish cutting position, they are held by any suitable device, a light shear bar 17 being shown spiked in the near 55 wall of the barrel, for each cutter. A back stop key 18 is also provided to prevent outward tilt of the relative cutter in its window slot 9a. Shearing load of the cutters 2 while in action on a fish is removed from the screws 10 by provision of a 60 hook 4a on the upper end of each block 4 to interlock with a relative keeper lug 5a on the upper end of the carrier 5.

Means are provided to prevent the spring 15 from forcing the set of cutters and their carrier 65 upward until a predetermined time as the positioning of the set of cutters at the desired elevation as to the fish body to be cut, and means are provided to effect the release of the carrier for action of the cutters at the proper time.

As here shown, the carrier is fixed to the foot 70 section of the barrel by a plurality of simple shear pins 20, which may be screwed into the wall of the barrel for ready renewal at will, and are transverse to vertical ways or channels 21 along 75 the outer surface of the carrier 5 and in which

ways there are slidable blades 22 whose lower ends are designed to engage the shear pins 20 when enough tension is placed on the barrel string or tool to cut through the pins 20.

The shear blades 22 are rigidly fixed to crown 5 ring 23 which is slidably confined in the barrel section 6 for movement endwise between a shoulder 24 of the barrel and the lower end of collet 25 slidably and turnably fitting the barrel bore above the shoulder 24, and designed to move up 10 against a stopping shoulder 26 formed by the lower end of the barrel section 7.

As indicated at X, Fig. 1, the stroke of the crown ring 23 is limited to a degree about equal to the diameter of the shear pins 20 so that that 15 will be the total amount of pulling lift on the tool to effect the cut of the pins 20 and the full release of the carrier 5 so that this can be automatically propelled to lift the set of cutters to break their keys or bars 17 and thrust them in- 20 ward against the fish body B. The collet 25 is normally held in upper position by the crown ring 23 and is provided with a set of inwardly springing arms or dogs 27 designed to snap in- 25 wardly under collars or shoulders C as encountered by downward movement of the tool barrel along the fish body B.

When the tool barrel has been lowered to the lowermost possible position, or level thereabove desired, the string is gradually elevated to bring 30 the dogs 27 up against the next supra-adjacent collar C after which enough strain will be placed on the string to cause the shear blade ends 22 to cut through the shear pins 20 as the barrel is pulled up as to the arrested dog collet 25, a dis- 35 tance indicated at X; which of course is arbitrary. The dogs 27 are pulled up to the collar C to arrest the collet 23 only to effect the shearing of the pins 20 and not to use the collar C as a buttress for reaction of the motor spring 15. 40 Therefore, as soon as the pins are cut the whole tool can be moved down on the pipe or fish B and the motor spring is in full effect against the carrier 5, without any support from the pipe collar C, to forcibly tilt the cutters 2 inwardly without 45 lean-to of the dogs 27 on the pipe collar C since the motor spring 15 has its buttress seat on a part of the barrel 6 of the tool and reacts at its opposite end directly on the carrier 5.

Immediately the cutter carrier 5 is free of the 50 barrel pins 20, the motor spring 15 acts to bodily push up the set of cutters 2 to break their keys 17 and then to ram the free ends of the cutters 2 inwardly into cutting engagement with the fish body B.

However the cutters will not cut into the body until the tool string is rotated, normally to the right (looking down on the tool). It will be seen therefore, that the barrel assembly and tool string can be bodily lowered to bring the cutter 60 ends to any desired level below the collar C at which the cutter carrier 5 was released and above the next lower collar on the fish. At such desired level the tool string and its barrel assembly can now be rotated and the fish cut into by the 65 orbitally driven cutters.

While the cutter carrier 5 and the shear blade ring 23 are co-rotatively united by the shear blades 22 and are rotated by the spline blocks 4 in the barrel section 6, the dog collet 25 is free 70 for relative rotation of the barrel in event the dogs should bind on the engaged fish.

In Fig. 3 a fish-engaging set of "slips" 30 are attached by spring arms 31 to a tubular coupler 32 slidably and turnably fitting a barrel section 75

33 which has one or more clutch nogs 34 inwardly projecting to hook into a bayonet slot 35 therefor in the upper end of the coupler 32. By left-hand turn of the tool string and barrel 33 the set of slips 30 are unlocked and the barrel may be pulled up while friction spring bows 36 fixed on the coupler 32 will firmly drag on the apposed fish over which the barrel may have been lowered.

10 Continued lift of the barrel will move a liner 37 having a conical seat 38 up to engage the complementary slips 30 and these will be concurrently moved inwardly of the liner and will solidly pinch on the intruded fish body, in a manner well known in the art of rotary well drilling tools. As soon as the slips have set on the fish, the liner 37 will be arrested and further upward movement of the barrel 33 will cause shear blades 22^a fixed to a collet 37 to cut free a relative cutter carrier 20 5, as fully above described.

It is understood that this novel cutting mechanism is not limited to use only in the assembly here exhibited.

This invention has for an object to eliminate the use of the "fish" or other pipe or part as an essential means to rotate the cutters, that is tilt them, into engagement with the "fish" or work part as is old in the art in Patent No. 1,625,414, April 19, 1927, to Kammerer, and Patent No. 30 1,625,391, of same date, to Reilly et al.; a further object being to eliminate the proposed use of a column of liquid for producing pressure for tilting the cutter blades as suggested in Fig. 7 of said Reilly et al. patent, and an object is to eliminate 35 the need of pulling the tool string body upward to use the fish collar as a support to effect the actual inward tilt of the cutters after they have been released by reaction of the collar on a shearing means. These purposes are had and the disadvantages are overcome by the tool herein above disclosed.

What is claimed is:

1. A tool of the class described including a tubular body, a reciprocative set of inwardly tilt-45 able cutters in the body, a spring seated on a fixed part of the body for automatically sliding the set in one direction, means to tilt the sliding cutters, means normally restraining the sliding of the set, and means slidably in the body to engage and disrupt the restraining connection without action on the spring.

2. A tool of the class described and including a rotary barrel and having a carrier splined therein, a set of inwardly tilttable cutters on the carrier, means for automatically projecting the carrier in one direction, means for normally restraining the carrier, means slidably in the barrel to release the carrier upon a relative shift of the barrel as to the last named means and including means holdably engageable with a body to be severed and is operative on the sleeve means upon a relative shift of the said body.

3. A tool as set forth in claim 1, and including means mounted in the barrel for individually, 60 positively but releaseably holding the cutters in non-effective position.

4. A tool as in claim 1, and including a body engaging means, independent of the cutters, controlling the release of the cutter carrier.

70 5. A circumorbital, body severing tool including a rotary barrel, means slidably mounted on the barrel to holdingly set on the body against end shift, slidable and tilttable cutting means on the barrel and means for automatically thrusting the same to cutting position, means normally

restraining the sliding function of said cutting means, and means for releasing the restraining means for action when the holding means is effective and as the barrel is subsequently shifted on the holding means; said automatic means acting independently of the body after release is effected to tilt the cutters.

6. A tool as in claim 5, and in which the cutting means is shifted to cutting position by the automatic means after the barrel has been arrested by the effective holding means; and the tool assembly being lowerable bodily after such release action to effect a cut at desired level.

10 7. A circumorbital pipe, stem or other body severing tool including a rotary barrel, means movably mounted on the barrel for holding engagement with and against shift on the body to be cut, an automatic device slidably mounted on the barrel in normally restrained relation thereto and active independently of the holding means, and cutting means carried by said device and actual thereon and thereby to a cutting position on the body; said holding means operative by work abutment to release the restrained device and the released device operative at any level 20 25 desired, without work abutment, to tilt the cutters inwardly.

8. A circumorbital set of cutters, means for positioning the cutters in ineffective relation on a body to be severed and for rotating the set 30 when in effective position, restrained means slidably splined in the positioning means and carrying and for automatically thrusting the cutters to effective position on the body, and means engageable with the body for releasing the restrained means, the set of cutters being operative independently of support by the body, after the set is released.

9. The combination as in claim 8, and in which the carrying means shifts to set the cutters whilst 40 the positioning means is held in arrest by the body or when the last named means is shifted without such arrest.

10. A circumorbital set of cutters, a barrel for positioning the cutters in ineffective relation on 45 work to be severed and for rotating the set of cutters when in effective position, a cutter carrier and means for shifting it along the barrel automatically and which is in restrained position when the cutters are in ineffective relation, and 50 means movably carried by the barrel and engageable with the work for releasing the restrained carrier whilst the barrel is arrested by such work engagement the automatic means operative, after such release, independently of work support.

11. A tool of the class described including a tool string element and a carrier slidably splined thereon and having a set of circumferential cutters operatively mounted thereon releasable means to restrain the carrier with cutters retracted, means to engage the work to effect release of the carrier, and means for automatically shifting the carrier to apply the cutter to the work free of any end thrust support or holding effect by the work so that the cut can be made 60 at any desired level after the carrier is released.

12. A tool of the class described having a string barrel provided with a set of cutters relatively slidable as to the barrel and pivoted independently of each other, and work controlled means for automatically sliding the cutters to work engaging position whilst the barrel is free of end support by the work and a restraining connection between the barrel and the set of cutters which is disrupted by operation of the work 70 75

controlled means during a given movement of the barrel as to the work.

13. A tool as in claim 12, and said controlled means including a connector working in the barrel adapted to holdingly interengage with the work and a spring actuated cutter to tilt the cutters without aid of the work.

14. A tool of the class described including a tool barrel, a set of tilttable cutters slidably splined in the barrel, means for automatically sliding the set in one direction in the barrel, means to tilt the sliding cutters, means normally restraining the sliding of the set, and work controlled means to disrupt the set restraining connection.

15. A tool of the class described including a rotative, string barrel tool having a slidable set of tilttable cutters, shearable means connecting the set to the barrel, work controlled means for disrupting the shearable means, and means for automatically sliding the set in the barrel to tilt the cutters to work engaging position independently of end thrust support by the work.

16. A tool string barrel having a slotted wall

section, a carrier slidably fitted in the barrel, spline blocks removably attached to the carrier and applicable thereto through the wall slots, and holding the carrier against relative rotation and work-engaging cutters pivoted on the carrier blocks, and being removable with the blocks through the slots.

17. In a tool of the class set forth, a string barrel, a cutter carrier slidably mounted in the barrel, shearable means temporarily connecting the barrel and the carrier, a shearing device for said means slidably mounted in the barrel, and a relatively rotatable, work-controlled means for effecting operation of the said device.

18. The assembly as set out in claim 17, and in which the said device includes shear blades slidably splined in the carrier.

19. An assembly as in claim 17, and including means for automatically motivating the released cutter carrier.

DONALD U. SHAFFER.

FRANK D. HOBBS.

EDWARD C. HAMM.
